UNITED STATES PATENT OFFICE.

EDWARD L. McCALAIN, OF GREENFIELD, OHIO, ASSIGNOR TO THE AMERICAN PAD & TEXTILE COMPANY, OF GREENFIELD, OHIO, A CORPORATION OF OHIO.

CLAMP FOR HORSE-PADS.

No. 900,946.

Specification of Letters Patent.

Patented Oct. 13, 1908.

Application filed November 18, 1904. Serial No. 233,238.

To all whom it may concern:

Be it known that I, EDWARD L. McCALAIN, a citizen of the United States of America, and resident of Greenfield, county of Highland, State of Ohio, have invented certain new and useful Improvements in Clamps for Horse-Pads, of which the following is a specification.

The object of my invention is a clamp for horse pads which may be swung to one or the other side of the pad to engage and hold the harness thereon, so that the pad may be reversed to allow either one or the other of its sides to contact with the horse. This object is attained by the means described in the specification and illustrated in the drawings, in which

Figure 1 is a plan view of a collar pad supplied with a clamp embodying my invention. Fig. 2 is a perspective view of a collar pad with a collar thereon held in place by the clamp embodying my invention. Fig. 3 is a sectional view through a pad showing it with the clamp thrown to each side of the pad and engaging collars upon each side. Fig. 4 is an enlarged perspective view of a clamp embodying my invention. Fig. 5 is a similar view of a metallic clip for holding the clamp upon the pad.

Referring to the parts: Pad, A, has secured near its edge clips, B. Clamp, C, is formed from a flat strip of spring metal curved in the form of a circle and having upon one side a journal loop, c. Journal loop,

c, is to engage the metallic clip, B, so that the clamp may be rotated about the clip as a center.

It is seen the clips being secured near the edge of the pad, that the clamps may be swung to either one or the other side of the pad, as shown in Fig. 3.

In the form illustrated in the drawings, I have shown the clamp as secured to a collar pad to engage a horse collar, D, but it is obvious that the clamp might be applied to other forms of pads for engaging other pieces of harness.

It is seen that when a pad is provided with clamps embodying my invention, either one or the other side of the pad may be placed next to the horse and the clamps be swung to the upper side thereof. This increases the life of the pad approximately two-fold.

What I claim is:

The combination of a sweat pad, clips, each consisting of a bar of metal having eyes for ends, the clips being secured to the edge of the pad by means of the eyes, clamps, each formed from a flat strip of spring metal which is curved in the form of a circle and bent outward upon one side into a journal loop, and each loop journaled upon the bar of metal so that the clamp may be rotated about the clip.

EDWARD L. McCALAIN.
